UNITED STATES PATENT OFFICE.

JOHN T. LITTLE, OF NASHVILLE, TENNESSEE.

PLUG-CUTTING MACHINE.

1,150,279.

Specification of Letters Patent.

Patented Aug. 17, 1915.

Application filed June 27, 1913. Serial No. 776,147.

To all whom it may concern:

Be it known that I, JOHN T. LITTLE, a citizen of the United States, residing at Nashville, in the county of Davidson and State 5 of Tennessee, have invented certain new and useful Improvements in Plug-Cutting Machines, of which the following is a specification, reference being had to the accompanying drawings.

10 This invention relates to an improved plug cutting machine primarily designed for use in cuttings plugs for plugging knot holes in lumber used for commercial purposes, such as the construction of burial caskets.

15 Another object of my invention is to produce a plug cutting machine of the above character embodying a tubular saw, and a spring pressed plunger provided with a head acting to force the plug cut from the lumber out of the opening created in the cutting 20 operation of the saw.

It is a further object of the invention to produce a machine of the above character which is simple in its construction, durable 25 and reliable in operation and may be constructed at comparatively small manufacturing cost.

With the above and other objects in view as will become apparent as the description 30 proceeds, the invention consists in certain constructions, combinations and arrangements of the parts that I shall hereinafter fully describe and claim.

For a full understanding of the invention, 35 reference is to be had to the following description and accompanying drawings, in which—

Figure 1 is a side elevation of a plug cutting machine embodying the present invention; Fig. 2 is an enlarged vertical section; Fig. 3 is a section taken on the line 3—3 of Fig. 2; Fig. 4 is a detail perspective view of the saw. Fig. 5 is a detail perspective view of the collar.

40 In the construction of burial caskets and similar manufactures in which cloth covered or veneered lumber is used, the lumber contains many imperfections and in many instances is so greatly weakened by numerous 45 knot holes and similar defects that it cannot be used. Thus considerable waste results.

It is the principal object of my invention to produce a simple and highly efficient machine for quickly cutting plugs to be secured 50 by glue or similar adhesive in the holes of the lumber, whereby waste of the material

is minimized, and considerable economy in the manufacture of burial caskets and similar articles effected.

Having thus outlined the primary purpose 60 of my invention, I will now proceed with a detail description of its construction and operation.

Referring in detail to the drawings, 5 designates a bracket which is secured to an upright or other stationary support, said bracket including the lower and upper arms 6 and 7 respectively. The upper arm of the bracket is formed with a broad supporting plate 7' whereon the operating motor 8 is 65 disposed. A motor shaft 9 is coupled to the upper end of a vertically disposed shaft 10, the opposed ends of the motor shaft 10 being provided with disks 11 and 12 respectively 70 between which the fiber disk 13 of paper or other material is arranged, said latter disk being provided with cylindrical sockets or recesses 14 to receive the pins or studs 15 carried by the disks 11 and 12. The vertical shaft 10 is mounted to rotate in a bushing 16 75 arranged in the outer end of the upper bracket arm 7, and suitable ball bearings indicated at 17 support the vertical shaft, said bearings being arranged above and below the bracket arms 6.

The lower end of the shaft 10 is enlarged 80 and provided with exterior screw threads 18 to receive the interior threads upon the upper end of a hollow mandrel 19. This mandrel extends through a bushing 20 arranged 85 in the lower bracket arm 6. The outer face of said bushing tapers longitudinally from its lower to its upper end, the bracket arm and semi-circular yoke or collar 22 being provided with similarly tapered recesses 21 90 through which said bushing extends. The upper end of the bushing is exteriorly threaded to receive a lock nut 23. The collar 22 is provided with a ring or annulus 24 upon one of its ends which receive the 95 lower larger end of the bushing 20. The lower end of the mandrel 19 is exteriorly threaded as shown at 25 to receive a clamping nut 26, the purpose of which will be later explained.

100 Within the hollow mandrel 19, a tubular saw 27 is arranged, the tube closely engaging the wall of the mandrel and extending downwardly beyond the lower end thereof. The lower end of this tube is provided with 105 spaced open ended slots 28 whereby a series of tongues 29 are formed. The lower end

edges of these tongues are provided with saw teeth 30 which perform the cutting action. The mandrel 19 is provided in its lower end with a plurality of longitudinally extending slits 31. Thus a series of separated threaded sections are provided upon the lower end of the mandrel, and the nut 26 has a tapering threaded bore for engagement upon the tapered threaded end of the mandrel. The tubular saw 27 is provided in its upper end with a notch or recess 27' to receive a pin 32 extending into the bore of the mandrel whereby the saw is held against rotation. The upper end of the tube is disposed in the enlarged lower end of the mandrel bore and fits against an annular shoulder 19' as shown. By adjusting the nut 26 upon the lower end of the mandrel, the separated threaded portions of said mandrel are forced into clamping engagement with the tubular saw 27, so that the same is tightly clamped in position. Two of the tubular saws 27 are provided with each machine, one for cutting out the plug and the other of slightly larger diameter for cutting the hole or opening in the timber to be filled by the plug.

Within the tubular saw 27, and mandrel 19, a hollow plunger 33 is arranged for vertical movement. In the upper end of this plunger, a suitable head 34 is secured to close the same and to the head the lower end of the plunger rod 35 is connected. The upper end of said rod is movable in a longitudinal guide bore 36 formed in the lower end of the vertical shaft 10. A heavy coil spring 37 is arranged upon the rod 35 and bears at its upper end against the lower end of the shaft 10 and has its lower end engaged with the upper end of the plunger 33. A transversely disposed pin 52 extends through the upper end of the tubular plunger and has its ends movably disposed in longitudinal slots 53 provided in the wall of the hollow mandrel 19. A sleeve 54 is slidably engaged upon the mandrel 19 to retain the pin 52 in place and may be secured over the slots 53 to prevent the entrance of foreign matter therethrough by means of a set screw 55. In the lower end of the plunger, a presser head 38 is removably secured in any preferred manner. The lower face of this head is rounded or convex as indicated at 39 and is adapted to bear upon that portion of the lumber which is being cut out by the series of saw teeth 30.

From the above description, the operation of my invention will be fully understood. The lumber is arranged upon a suitable table which of course, is located immediately be-

neath the cutting teeth 30. Suitable means is provided for raising the table so as to bring the work arranged thereon into contact with the saw. The operating motor 8 is now set in operation so that the several series of teeth 30 upon the lower end of the saw 27 cut through the lumber. The circular plug which is then cut out of the lumber is engaged by the presser head 39 in the lower end of the plunger 33, and during the cutting operation this plunger is forced upwardly and the spring 37 gradually placed under compression. When the cutting operation is completed, said spring expands and the head 39 forces the plug from the opening cut by the saw teeth 30. The plugs which are cut in the manner above described are secured by glue or other suitable adhesive in the knot holes or other openings in the lumber to be used in the construction of the casket. It will be seen from the foregoing that I have produced a simply constructed and very efficient plug cutting machine whereby a large number of plugs may be easily and quickly cut. While I have above described the preferred construction and arrangement of the several elements employed, it is to be understood that my invention is susceptible of considerable modification therein without departing from the essential features or sacrificing any of the advantages of the same.

Having thus described the invention, what is claimed is:

In a machine of the character described, a rotary mandrel, a tubular saw secured in one end of said mandrel, said mandrel being provided intermediate of its ends and at diametrically opposite points with opposed slots, a plunger longitudinally movable in said mandrel and saw, a transversely disposed pin removably engaged in one end of said plunger and having its opposite ends disposed in the respective slots in the mandrel, and a sleeve loosely engaged upon the mandrel for longitudinal movement adapted to be arranged over said slots to close the same and prevent movement of said pin outwardly through the slots, and also prevent the entrance of foreign material to the interior of the mandrel through the slots, said sleeve being provided with a set screw whereby the same may be secured upon the mandrel in its adjusted position.

In testimony whereof I hereunto affix my signature in the presence of two witnesses.

JOHN T. LITTLE.
